CHARGE FORMING DEVICE

Application filed May 23, 1930. Serial No. 454,917.

This invention relates to charge forming devices for internal combustion engines, and more particularly to devices of the type having means for forming a primary mixture of air and liquid fuel which is delivered to a secondary mixing chamber or chambers, to be mixed with air therein under certain operating conditions.

Devices of this character are shown in the copending applications of Wilford H. Teeter, Serial No. 288,685, filed June 27, 1928, and Fred E. Aseltine et al., Serial No. 370,179, filed June 12, 1929.

In the device disclosed in the above mentioned applications, means have been provided for maintaining at the fuel inlets substantially the static suction of the air chamber which is controlled by a spring held air valve. It has been found, however, that because the passages which convey air from the air chamber to the fuel inlets and also communicate the suction of the air chamber thereto, are of varying lengths, and the inlets thereof are differently positioned with respect to the incoming current of air, the suction maintained at the different nozzles is not exactly the same.

It is the object of this invention to provide means for maintaining exactly the same degree of suction at all of the fuel inlets and exactly the same flow of fuel from each of said inlets under any given operating condition, preferably in a charge forming device in which substantially a static suction is maintained at the fuel inlets.

According to the present invention, this is accomplished by the provision of passages which communicate the suction of the air chamber to the fuel jets and also convey air from said air chamber to the jets, said passages being of exactly the same length so that the air from said air chamber travels the same distance before coming in contact with each fuel inlet, the inlet ends of said passages also being arranged concentrically with respect to the air valve so that they are shielded from the incoming current of air to the same extent whereby impact action of the entering air on the inlet ends of said pas-

sages and the velocity of the air through all of said passages is the same.

Further objects and advantages of the present invention will be apparent from the following description, reference being had to the accompanying drawing wherein a preferred embodiment of one form of the present invention is clearly shown.

In the drawing:

Fig. 1 is a vertical section through a charge forming device constructed in accordance with the present invention and showing one outlet branch of the manifold.

Fig. 2 is a section on the line 2-2 of Fig. 1.

Fig. 3 is a fragmentary detail section showing the fuel passage leading to the fuel inlets.

The present invention is disclosed herein as embodied in the charge forming device of substantially the same general construction as is illustrated in application Serial No. 370,179, and for this reason a specific description of most of the structure other than those particular elements which comprise this invention or are directly associated therewith, have been omitted.

The device comprises a main air manifold 10, having three outlet branches, each of which is adapted to communicate with one of the intake ports of a multi-cylinder engine, the middle branch 12 being shown herein. These branches are each provided with an attaching flange 14 for securing the manifold to the engine block in the usual manner. Adjacent its inlet, the manifold is provided with a flange 16 to which the carburetor unit is adapted to be secured, as shown in Fig. 1.

The carburetor unit comprises the main housing 18, which is provided with a flange 20 adapted to be secured by screws 23 to the flange 16. An air inlet coupling 22 is secured in an opening in the top of the housing in any desirable manner, while a casting 24 in which the fuel passages conveying fuel to the fuel inlets are formed, is secured by screws 26 to the bottom of the main housing, a suitable gasket being provided to prevent leakage. A sheet metal fuel bowl 28 is held tight against a flat surface on the main hous- 100

ing by a screw 30, and fuel is maintained at a substantially constant level in the bowl by any conventional means.

A plurality of angular primary mixture passages indicated by the reference character 32, are formed in the lower part of the main housing and the vertical portions of these mixture passages communicate with a main air chamber 34 hereinafter more fully described. Fuel is admitted to these passages by means hereinafter fully described, is mixed with air therein and the resultant mixture conveyed through the mixture passages and conduits formed in the manifold to the secondary mixing chambers formed in the manifold outlet branches. One of said conduits is disclosed herein and comprises a sheet metal tube 36 which is cast in position in the manifold, this and the other primary mixture conduits associated with the end branches of the manifold being of identical construction with those disclosed in application Serial No. 370,179.

The primary mixture passages are controlled by a single throttle valve 38, which extends across all of the passages and is provided with grooves 40, which register with said passages. The grooves 40 merge into smaller grooves 42, which are adapted to provide passage for sufficient fuel to operate the engine when idling, said grooves being open when the throttle is in closed position.

All of the air admitted to the air chamber 34 is supplied through the coupling 23 and is controlled by a valve 44 normally held against its seat 46 by a spring 48 received between the valve and a flange 50 projecting from a sleeve 52 slidably mounted on a guide sleeve 54 which is fixed in any desirable way in the main housing and guides the air valve stem 56. Under normal operating conditions, the sleeve 52 occupies the position shown in Fig. 1, but may be lifted to close the air valve by a choke lever 58, which projects into the housing beneath the flange 50 and is operated by a mechanism fully shown in application Serial No. 370,179.

The valve 44 admits air to the chamber 34, which communicates directly with the primary mixture passages, as hereinbefore described, and also supplies air to a secondary air passage 60, which communicates with the manifold inlet and is controlled by manually and suction operated valves 62 and 64, secured to shafts 66 and 68 respectively.

The operating means for the throttle and the above mentioned valves is not illustrated herein, it being sufficient for the purposes of this disclosure to state that the valve 62 is adapted to be operated by the primary throttle 38, but the operating mechanism is so designed that the throttle has a certain independent movement toward its open position before the valve 62 begins to move, this degree of movement being generally such as to

enable the throttle to be opened to a position corresponding to the vehicular speed of approximately 20 to 25 miles an hour. After the throttle moves beyond this position, the throttle and the valve 62 move simultaneously, while the valve 64 is opened entirely by engine suction and only subsequent to the opening of the valve 62.

Opening movements of the valve 44 are temporarily retarded to prevent fluttering of the valve and leaning of the mixture, by a dashpot comprising a cylinder 70 formed in the casting 24 and a piston 72, secured to the lower end of the valve stem in any desirable manner and operating within the cylinder. The suction operated valve 64 is also provided with a dashpot to temporarily retard its opening movements, this dashpot and that described briefly above being of the same construction as fully disclosed in application Serial No. 370,179. All of the mechanism hereinbefore referred to is old in application Serial No. 370,179, and the improvement which constitutes the present invention, will now be described in detail. This invention relates to the fuel supply means which comprises a vertical fuel passage 74 formed in the casting 24, and closed at its lower end by a plate 76, which is screwed to the bottom of the casting. Fuel is admitted to the passage 74 at all times and under all operating conditions by a fixed calibrated plug 78 screwed into the casting 24 horizontally, as shown in Fig. 3, while at relatively high speeds, additional fuel is supplied to the passage 74 through the calibrated plug 80, which is received in the enlarged lower end of such passage and through which the flow of fuel is controlled by a valve which is shown in application Serial No. 370,179. The passage 74 connects at its upper end with a fuel channel 82, formed in the top surface of the casting 24 and communicating directly with three fuel inlets 84, which supply fuel at idling directly to the mixture passages and three vertical fuel passages 86, through which fuel is supplied to the mixture passages under all other operating conditions, the admission of fuel to the passages 86 being controlled by calibrated plugs 88.

The passages 86 are parallel with the air valve stem and are arranged in the arc of a circle which is concentric whereby such passages are symmetrical with respect to the periphery of the air valve. Each of the passages 86 at its upper end, connects with a horizontal passage 90, which connects with a vertical passage 92. Each passage 92 communicates at its lower end with a fuel supply orifice 94, which communicates directly with the associated primary mixture passage, the orifice being of much smaller size than either of the passages 88 and 90, as shown in Fig. 1. The passages 90 are supplied with air from

the main air chamber 34 through the medium of an arcuate slot 96, which is arranged concentrically with the air valve stem, and since the passages 92 and orifices 94 are also in an arc concentric with the valve stem, the three passages 90 are of exactly the same length and the air which enters the slot 96 and the fuel supplied through passages 86 flows exactly the same distance to each of the fuel supply orifices 94. Further, all parts of the slot 96 bear exactly the same relation to the periphery of the air valve and the velocity of the air which is admitted to said slot at all points should be exactly the same as will be more fully explained later.

The desirable results achieved by this device should be obvious. Since the passages from the air inlet ports 96 to the fuel feeding orifices 94 and the fuel passages from 20 plugs 88 to orifices 94 are all exactly the same length for each primary mixture passage, the frictional resistance to flow in such passages is clearly the same if the passages are of the same degree of smoothness. Moreover, since the air admission port 96 is in the form of a slot which is concentric with the air valve stem, it will be clear that all parts of this slot bear exactly the same relation to the periphery of the air valve and, therefore, there will be no variation in the velocity of the incoming air at various points throughout the length of the said port 96. Further, it will be noted that the flange 50 extends outwardly to a position beyond the outer edge of the port 96 and acts as a shield for such point preventing to a great extent the effect of impact of the entering air on the fuel as it issues from passages 86 and equalizing the effect of such impact as there is with respect to the several passages 86. It will be clear, therefore, that the air moves through the port 96 at relatively slow velocity and that the velocity of the air moving from the port to each fuel inlet orifice 94 is exactly the same, whereby the suction effective on the fuel feeding orifice 94 in each of said mixture passages is exactly the same, and the flow of the fuel therefrom is exactly the same at any time.

While the form of embodiment of the present invention as herein disclosed, constitutes a preferred form, it is to be understood that other forms might be adopted, all coming within the scope of the claims which follow.

What is claimed is as follows:

1. A charge forming device for internal combustion engines, comprising, a plurality of separate primary mixture passages adapted to supply a primary mixture of air and fuel to a plurality of separate secondary mixing chambers, means for supplying air to said primary mixture passages, means for supplying equal amounts of fuel to each of said primary mixing chambers comprising a fuel feeding orifice in each of said mixture

passages, fuel passages leading from a source of fuel supply to said fuel feeding orifices, and air inlet means supplying air to said fuel passages the same distance from each of said fuel feeding orifices, whereby the same amount of fuel is supplied to each of said mixture passages.

2. A charge forming device for internal combustion engines, comprising, a plurality of separate primary mixture passages adapted to supply a primary mixture of air and fuel to a plurality of separate secondary mixing chambers, means for supplying air to said primary mixture passages, a fuel feeding orifice in each of said mixture passages, and a common fuel supply channel for supplying fuel to all of said fuel feeding orifices, said orifices being equidistant from said fuel supply channel.

3. A charge forming device for internal combustion engines comprising, a plurality of separate primary mixture passages adapted to supply a primary mixture of air and fuel to a plurality of separate secondary mixing chambers, means for supplying air to said primary mixture passages, a fuel feeding orifice in each of said mixture passages, and a plurality of vented fuel passages of equal length conveying fuel to said fuel feeding orifices from a source of fuel supply.

4. A charge forming device for internal combustion engines comprising a plurality of separate primary mixture passages adapted to supply a primary mixture of air and fuel to a plurality of separate secondary mixing chambers, means for supplying air to said primary mixture passages, a fuel feeding orifice in each mixture passage for supplying fuel thereto, and means for supplying air to each of said fuel feeding orifices, comprising an air inlet port exactly the same distance from each of said orifices whereby the suction at said orifices is the same.

5. A charge forming device for internal combustion engines comprising a plurality of separate primary mixture passages adapted to supply a primary mixture of air and fuel to a plurality of separate secondary mixing chambers, means for supplying air to said primary mixture passages, a fuel feeding orifice in each mixture passage for supplying fuel thereto, fuel passages leading from a source of fuel supply to each of said fuel feeding orifices and means for admitting air to said fuel passages the same distance from each fuel feeding orifice.

6. A charge forming device for internal combustion engines comprising a plurality of separate primary mixture passages adapted to supply a primary mixture of air and fuel to a plurality of separate secondary mixing chambers, means for supplying air to said primary mixture passages, fuel passages leading from a source of fuel supply to each

of said mixture passages, an arcuate slot admitting air to said fuel passages and a plurality of fuel feeding orifices communicating with said fuel passages and arranged in the 5 arc of a circle concentric with said arcuate slot.

7. A charge forming device for internal combustion engines comprising a plurality of separate primary mixture passages adapted to supply a primary mixture of air and fuel to a plurality of separate secondary mixing chambers, an air chamber supplying air to all of said primary mixture passages, a fuel feeding orifice in each of said mixture 10 passages, fuel passages leading from a source of fuel supply to each of said fuel feeding orifices, passages conveying air from the air chamber to said fuel passages, the inlet ends of said air supply passages being the same 15 distance from the fuel feeding orifices.

8. A charge forming device for internal combustion engines comprising a plurality of primary mixture passages adapted to supply a primary mixture of air and fuel to a plurality of secondary mixing chambers, an air chamber supplying air to all of said primary mixture passages, a fuel feeding orifice in each of said mixture 20 passages, fuel passages leading from a source of fuel supply to each of said fuel feeding orifices, and passages of larger size than the fuel feeding orifices for conveying air to the fuel passages, whereby the static suction of the air chamber is communicated to said fuel passages, the 25 inlet ends of said air supply passages being the same distance from the fuel feeding orifices.

9. A charge forming device for internal combustion engines comprising a plurality of primary mixture passages adapted to supply a primary mixture of air and fuel to a plurality of secondary mixing chambers, an air chamber supplying air to all of said primary mixture 30 passages, an air valve controlling the admission of air to said chamber, a fuel feeding orifice in each of said mixture passages, fuel passages leading from a source of fuel supply to said fuel feeding orifices, and an arcuate slot which is concentric with the periphery of the air valve, for admitting air to 35 all of said fuel passages.

10. A charge forming device for internal combustion engines comprising a plurality of primary mixture passages adapted to supply a primary mixture of air and fuel to a plurality of secondary mixing chambers, an air chamber supplying air to all of said primary mixture 40 passages, an air valve controlling the admission of air to said chamber, a fuel feeding orifice in each of said mixture passages, said orifices being arranged in an arc concentric with the periphery of the air valve, fuel 45 passages leading from a source of fuel supply to said orifices, and an arcuate slot for admitting air to said fuel passages, said slot

also being concentric with the periphery of said air valve.

11. A charge forming device for internal combustion engines comprising a plurality of primary mixture passages adapted to supply a primary mixture of air and fuel to a plurality of secondary mixing chambers, an air chamber supplying air to all of said primary mixture 50 passages, an air valve controlling the admission of air to said air chamber, a plurality of fuel passages substantially parallel to the path of air entering the air chamber and through which fuel flows in a direction opposite to that of the entering air, and air supply means also arranged in an arc 55 concentric with the periphery of the air valve to supply air to mix with the fuel issuing from said fuel passages, whereby the impact of the entering air on the delivery end of each fuel passage is the same.

12. A charge forming device for internal combustion engines comprising a plurality of primary mixture passages adapted to supply a primary mixture of air and fuel to a plurality of secondary mixing chambers, an air chamber supplying air to all of said primary mixture 60 passages, an air valve controlling the admission of air to said air chamber, a plurality of fuel passages substantially parallel to the path of air entering the air chamber and through which fuel flows in a direction opposite to that of the entering air, and an arcuate slot substantially in alignment with said fuel passages and admitting air to mix 65 with the fuel issuing therefrom, said slot lying in an arc concentric with the periphery of the air valve whereby the impact of the entering air on the delivery end of each fuel passage is the same.

13. A charge forming device for internal combustion engines comprising a plurality of primary mixture passages adapted to supply a primary mixture of air and fuel to a plurality of secondary mixing chambers, an air chamber supplying air to all of said primary mixture 70 passages, an air valve controlling the admission of air to said air chamber, a plurality of fuel passages substantially parallel to the path of air entering the air chamber and through which fuel flows in a direction opposite to that of the entering air, an arcuate slot substantially in alignment with said fuel 75 passages and admitting air to mix with the fuel issuing therefrom, said slot lying in an arc concentric with the periphery of the air valve whereby the impact of the entering air on the delivery end of each fuel passage is the same, and a shield over the slot for minimizing the effect of impact.

14. A charge forming device for internal combustion engines comprising a plurality of primary mixture passages adapted to supply a primary mixture of air and fuel to a plurality of secondary mixing chambers, an air chamber supplying air to all of said primary mixture 80 passages, an air valve controlling the admission of air to said air chamber, a plurality of fuel 85 passages substantially parallel to the path of air entering the air chamber and through which fuel flows in a direction opposite to that of the entering air, an arcuate slot substantially in alignment with said fuel passages and admitting air to mix with the fuel issuing therefrom, said slot lying in an arc concentric with the periphery of the air valve whereby the impact of the entering air on the delivery end of each fuel passage is the same, and a shield over the slot for minimizing the effect of impact.

mary mixture passages, an air valve controlling the admission of air to said air chamber, a plurality of fuel passages substantially parallel to the path of air entering the air chamber and through which fuel flows in a direction opposite to that of the entering air, an arcuate slot substantially in alignment with said fuel passages and admitting air to mix with the fuel issuing therefrom, said slot lying in 5 an arc concentric with the periphery of the air valve whereby the impact of the entering

air on the delivery end of each fuel passage is the same, a fuel feeding orifice in each mixture passage and passages conveying an emulsion of fuel and air from the ends of said fuel passages to the fuel feeding orifices, said orifices being also in an arc concentric with the periphery of the air valve, whereby the fuel emulsion travels the same distance to each fuel feeding orifice. 70
